UNITED STATES PATENT OFFICE.

DAVID L. NEWCOMB, OF SAN DIEGO, CALIFORNIA, ASSIGNOR OF ONE-HALF TO JOHN LAWRENCE, OF SAN DIEGO, CALIFORNIA.

ROUNDABOUT FOR PLAYGROUNDS.

1,108,080.

Specification of Letters Patent.

Patented Aug. 18, 1914.

Application filed October 23, 1913. Serial No. 796,838.

To all whom it may concern:

Be it known that I, DAVID L. NEWCOMB, a citizen of the United States, and a resident of San Diego, in the county of San Diego and State of California, have invented certain new and useful Improvements in Roundabouts for Playgrounds, of which the following is a specification.

My invention relates to round-about 10 which are propelled manually and which are particularly adapted for play-grounds for children and the objects of my invention are, first, to provide a device of this class which will provide entertainment and exercise for the operators; second, to provide a device of this class which is simple and economical of construction and easy to operate; third, to provide a device of this class in which the danger of accident is minimized; 20 fourth, to provide a device of this class which operates on land similar to the rowing of a boat, and, fifth, to provide a new and novel means of manually operating a round-about.

25 With these and other objects in view as will hereinafter appear, my invention consists of certain novel features of construction, combination and arrangement of parts as will be hereinafter described in detail 30 and particularly set forth in the appended claims, reference being had to the accompanying drawings and to the characters of reference thereon, which form a part of this specification, in which:

35 Figure 1 is a top or plan view of the device complete, Fig. 2 is a sectional view through A—B of Fig. 1, and Fig. 3 is a detailed perspective view of the engaging portion of the operating lever, and one of its engaging 40 elements.

Similar characters of reference refer to similar parts throughout the several views.

The central support 1, center post 2, diagonal braces 3, horizontal supports 4, bearing 45 5, bearing 6, boats 7, hanger rods 8, levers 9, connecting rods 10, engaging feet 11, and sand box 12, constitute the principal parts of my structure.

50 The support 1, together with the bottom of the sand box 12, provides a base and support for the structure. Revolubly and vertically mounted in this support is the center post 2, and mounted on the support 1 and rigidly secured to the post 2 is the bearing 6. Mounted on the top end of this

central post 2 is the bearing 5. These bearings 5 and 6 are adapted to revolve on the center post, or the center post may revolve with them. The bearing 5 is provided with a plurality of extending sockets 5^a. In this case I have shown four for the purpose of illustration, but there may be any number desired. In these sockets are rigidly mounted the inner ends of the horizontal arms 4 which extend horizontally the desired distance. These horizontal arms are supported near their outer ends by means of the diagonal braces 3 which are mounted in sockets 6^a on the bearing 6 at one of their ends and at their other ends in the sockets 4^a, which are rigidly secured near the extended ends of the arms 4. These arms 4 are connected together at their outer ends by means of braces 13 which forms a rigid connection for the arms at their outer ends. Mounted in the outer end of each of the horizontal arms 4 is a vertical rod 8 which extends vertically downward, and upon the lower ends are mounted supports 14. Upon each of these supports 14, centrally between two adjacent horizontal arms, is a boat shaped carriage 7. This may be any shape desired, but is preferably boat-shaped as shown. Mounted on the inner edge of each of the boats is a lever support 7^a, shaped as shown best in Figs. 1 and 2, which is adapted to support the lever 9 and also limit its movement so that the levers in the various boats will not interfere with each other. Mounted on the inner ends of the levers 9 are connecting rods 10 upon which are mounted the engaging feet 11. Around the support 1 is an annular trough 12 which is partially filled with sand with which the engaging feet 11 contact, forming a means for moving the boats similar to the action of oars in the water. The lower surface of this trough is, however, provided with a notched or corrugated surface so that if the sand does not hold sufficiently the foot will engage with the notches and thus provide a good and sufficient means of moving the boats around by the action of the levers 9; the action being practically the same as rowing a boat.

Though I have shown and described a particular construction, combination and arrangement of parts, I do not wish to be limited to this particular construction, combination and arrangement, but desire to in-

clude in the purview of my invention the construction, combination and arrangement substantially as set forth in the appended claims.

5 It is obvious that with this construction there is provided a manually operated round-about which will provide exercise for children or adults, that is entertaining; that it is economical of construction and easily operated; that the results are similar to that of rowing a boat in the water; that when the oars are not being operated the feet 11 smooth the top surface of the sand; that when the round-about is going at a good velocity the oars may be stopped and the round-about will continue without being retarded to any extent; that the sand in the trough and the engaging feet are the principal motive element; that the notches in the 20 bottom of the same are only secondary.

Having thus described my invention, what I claim as new and desire to secure by Letters Patent, is:

1. A round-about comprising a rotatable 25 frame, carriages suspended therefrom, a trough of sand, and levers provided with feet adapted to engage with said sand, whereby said frame is rotated manually.

2. A round-about for play-grounds comprising a rotatable frame, carriages suspended therefrom, an annular trough of sand, and levers provided with feet adapted to engage with said sand, whereby said frame is rotated manually by a rowing motion.

3. A round-about comprising a base consisting of a bearing and an annular sand trough surrounding the same, a frame revolvably mounted in said bearing, a plurality 40 of boats suspended from said frame, sand in said annular trough, and means pivotally mounted on one edge of each of said boats engaging with the sand in said trough, whereby said frame is revolved by a rowing motion.

4. A round-about comprising a base consisting of a bearing and an annular sand trough surrounding the same, a frame revolvably mounted in said bearing, a plurality of boats suspended from said frame, sand in 50 said annular trough, means pivotally mounted on one edge of each of said boats engaging with the sand in said trough, whereby a rowing motion is produced and said frame revolved, and a plurality of 55 notches in the bottom of said trough adapted to facilitate the engagement of said means.

5. In a round-about for play-grounds, the combination of an annular box of sand, a 60 plurality of boats mounted so as to revolve around said box, and means mounted on each of said boats adapted to engage with said sand and when operated manually from said boats revolve the same.

6. A round-about for play-grounds comprising a central support or bearing, a central post vertically and revolvably mounted therein, a plurality of horizontal arms mounted on the upper ends of said post, 70 braces extending from near the lower ends of said posts to near the outer extended ends of said arms, a rod suspended from the outer end of each arm, supports mounted on the lower ends thereof, carriages mounted on said 75 supports, a sand trough surrounding said first mentioned support or base, a lever pivotally mounted on each of said boats, means for engaging with the sand mounted on the inner ends of each of said levers, whereby a 80 rowing motion is produced by the operation of said levers and said carriages revolved.

In testimony whereof, I have hereunto subscribed my name in the presence of two subscribing witnesses.

DAVID L. NEWCOMB.
